METHOD OF COATING SHEET METAL CAN
ENDSAlfred L. Kronquest, Syracuse, N. Y., assignor to
Continental Can Company, Inc., New York,
N. Y., a corporation of New York

Application November 7, 1936, Serial No. 109,765

1 Claim. (Cl. 113—80)

The invention relates to new and useful improvements in a method of coating a can end which is of sheet metal and adapted to be joined to a can body by rolling parts of the end and body into a seam. It is a well-known expedient to provide a can end with a channel at the peripheral edge portion thereof and apply to said channel a plastic coating material, and then to roll the edge portion of the end and a flange on 5 the can body into a seam. The plastic sealing material will fill all voids and irregularities in the metal and produce an hermetically sealed joint.

An object of the invention is to provide a novel 15 method of applying the coating material to the can end wherein the can ends are caused to travel along a predetermined path and are progressively engaged by a suitable coating applicator without interruption of their continuous travel.

20 A further object of the invention is to provide a method of the above type which is particularly adapted for applying a coating material to a can end having parallel sides and rounded corners.

In the drawing—

25 Figure 1 is a view in vertical section showing more or less diagrammatically an apparatus for carrying out the invention;

Fig. 2 is a plan view of the same with the conveyor chain omitted and the conveyor lug carried 30 thereby sectioned;

Fig. 3 is a sectional view through a portion of a can body and can end showing the parts assembled preparatory to the forming of the seam for joining the same, and

35 Fig. 4 is a view similar to Fig. 3, but showing the seam completed.

In Figures 3 and 4 of the drawing, I have shown a portion of the can end at 7 which is joined to a can body indicated at 5. The can body is 40 formed with a flange 6 in the usual manner, and the can end is provided with a peripheral channel portion 8 to which has been applied a plastic coating material indicated at 9. In Fig. 4 of the drawing, the metal parts are rolled into 45 a seam, and the plastic sealing material fills all voids and spaces formed by irregularities in the metal so that the joint is an hermetically sealed joint. This is a well-known type of joint and further description of the same is not necessary.

50 The coating material used in a seam of the above type may be of any approved composition having the quality of deformability or plasticity, so that when the seam is completed by the rolling of the parts, the coating material will effectively fill all voids and spaces caused by the

irregularity of the metal and thus produce a sealed joint.

The present invention has to do with a method of applying the coating to the can end. In the drawing, a can end is illustrated which has parallel sides and ends with rounded corners. A great deal of difficulty has been experienced in coating a can end of this type. The usual method is to cause a coating nozzle to travel in a path conforming to the channel in the can end for 10 supplying the coating material thereto. The irregularity of the path reduces the speed of the machine and the efficiency of the application of the coating to a certain extent. According to the present method, the coating is applied to the can 15 end by an applicator which rotates and is brought progressively into contact with the can end so as to apply the coating to the flanged portion or channel of the can end.

In the apparatus illustrated for carrying out 20 the method, there is shown a guideway 11 for supplying the can ends and for guiding them as they are moved along in a predetermined path, which as illustrated, is a rectilinear path. The movement of the can ends along the guiding 25 channel is accomplished by a conveyor chain 12 equipped with suitably spaced lugs 13 which contact with the can end and pushes the same along the guiding channel. The coating material which is to be applied to the can end is placed in a tank 30 indicated at 15. The coating material is indicated at 16. This tank is located directly beneath the guideway 11, and the rails of the guideway are cut out as indicated at 14 in the drawing so as to provide an opening over which the can end travels. The opening is so dimensioned that as the can end travels over the same, the channel will be progressively exposed so that an applicator may contact with the under side of the channel. The applicator, as illustrated, is in the form of a roller 17. This roller is engraved or otherwise formed on its periphery with an applicator rib 18, which rib in its development conforms to the channel in the can end. The roller is rotated by suitable means which also operates 35 to move the conveyor so that the two are accurately timed whereby the driving lug 13 will present the can end with its channel 8 positioned for progressively registering with and contacting with the applicator rib 18. The roller is 40 so disposed relative to the bath of coating material in the tank 15 that the surface of the applicator rib passes beneath the surface of the coating material. The coating material will adhere 45 to the applicator rib and form a layer of coating 50

55

material thereon. A doctor 19 is positioned a slight distance away from the circumferential surface of the rib 18 and will strip excess coating material from the rib leaving a film of uniform thickness of coating material adhering to the rib. The can end and applicator are timed so that when the channel reaches the position shown in Fig. 1, the forward portion of the applicator rib 18 will engage within the channel and the coating material adhering to the applicator rib will also adhere to the can end and a sufficient amount of coating material transferred to the can end so as to provide the necessary sealing gasket for sealing the joint as described above. As the applicator continues its rotation, the can end continues its movement and progressively the applicator rib will contact with the forward curved portions of the channel, then the side portions of the channel, then the rear curved portions of the channel, and finally the rear side portion of the channel in the can end, as viewed in Fig. 2 wherein the arrows indicate the direction of travel of the can end and the direction of rotation of the applicator. It will thus be seen that by my improved method of coating, the can end travels continuously and is brought into register with the applicator rib, which in a sense, travels with the can end while it is applying the coating to the channel of the can end. However, a different portion of the applicator rib contacts with the can end so that the applicator rib rolls into the channel at the front side of the can end and then along the channel and out of the channel at the rear side of the can end. While the method is shown as applied to the coating of a so-called square can end, it is understood that it can be applied to round can ends, oval can ends, and can ends of any shape. The applicator, in each instance, is shaped to conform to the channel which is to be coated so that it will make progressive contact therewith as the

can end travels across the same. It will be noted that the guideway 11 of the can end is so constructed that the can end is held in a fixed path of travel and restrained against upward movement when the coating material is being applied thereto. The periodic progressive contact of the can ends with the applicator rib is characterized as a progressive rolling contact, for the reason that the can end travels in a rectilinear line relative to the applicator and the applicator roller 10 turns, makes contact with the traveling end and progressively changes the point of contact, finally leaving the rear end of the can end as it is traveling.

It is obvious that the method is not limited to the particular apparatus shown and described, but may be carried out in various other ways.

Having thus described the invention, what I claim, as new and desire to secure by Letters Patent, is—

The method of coating with sealing compound can ends having a channel at the peripheral edge thereof which is irregular in contour relative to the center of the can end, consisting in moving the can end during coating in a path lying in a plane parallel with and above the surface of a sealing compound coating bath, causing an applicator located between the bath and the can end and having a radially projecting coating rib on the surface thereof conforming in shape to the channel in the can end, to rotate about an axis parallel to said plane and at right angles to the direction of travel of the end, said applicator being disposed and timed so that the coating rib makes rolling contact with the surface within the channel of the can end to be coated, and also makes contact with the bath whereby sealing compound is lifted from the bath and applied within the channel of the can end.
